UNITED STATES PATENT OFFICE.

PAUL R. SAURER, OF NEW YORK, N. Y., ASSIGNOR TO THE PEELLE COMPANY, OF BROOKLYN, NEW YORK, A CORPORATION OF NEW YORK.

FIREPROOF ELEVATOR DOOR.

Application filed June 30, 1928. Serial No. 119,637.

My invention relates to fireproof elevator doors, and more particularly to the top bar structure of a door section of a type having an angle metal frame and a metal panel.

Elevator doors of the type to which my invention relates include door sections capable of movement upon vertical guides positioned upon opposite sides of a door opening within an elevator shaft. Such doors ordinarily comprise two sections simultaneously movable in opposite directions, although single section doors are sometimes used. The door of the invention, being particularly adapted for use with two-section doors, will be described in connection with a door of such construction.

Fireproof doors of the type to which my invention relates, when subjected to high temperatures or a sudden cooling after being subjected to such temperatures, not only expand or contract to a considerable extent, but when contracting, it has been found that the top bar of the upper section has a tendency to warp to an extent to leave a gap between this top bar and the wall of the elevator shaft adjacent the lintel of a door opening of sufficient width to form a passage for flame and smoke in sufficient volume to destroy the fireproof properties of the door to an extent to make such doors unsatisfactory as a means of reducing fire hazard.

To overcome this difficulty, fire underwriters have heretofore required that means be provided whereby when the door is in the closed position the top bar of the upper section be held, by means secured adjacent the lintel of the door, in a manner to prevent the warping of the door inwardly of the shaft upon the cooling of the metal of the top bar following its subjection to high temperatures. In some instances the holding of the top bar in a manner to prevent distortion or warping has been by means of interlocking channel bars, one of which is secured to the wall of the shaft above the lintel, and the other of which is carried by, and forms a part of, the top bar structure. Continuous channel bars have been found unnecessary and only narrow sections of such channel bars or hooks have been extensively used with like effect.

Ordinarily the top bars of the upper sections of counterbalanced, semi-automatic, or full automatic doors have secured thereto

metal bars, the weight of which is utilized 55 for balancing or overbalancing this section with relation to the lower section, which lower section ordinarily carries fittings not included in the upper section adding materially to their weight.

I have discovered that the distortion or warping of the top bar of the upper section is due in large measure to the presence of such counterbalancing or overbalancing bars, since the mass of the metal in such bars is so 65 much greater than that in the angle metal frame of the door section that such bars do not shrink or contract as rapidly as the angle metal top bar of the door section, and will thus offer resistance to the shrinkage of 70 said top bar in a line closely adjacent the outer edge of the horizontal angle of the bar while not interfering with such shrinkage along the plane of the vertical flange thereof. As a result of this condition, the said 75 vertical flange will shrink freely and thus cause the bar in its entirety to bend inwardly, or away from the wall, of the shaft, the extent of such movement at the middle of a ten or twelve foot door sometimes being as 80 great as three inches.

With the above conditions in mind, I have provided a construction of door wherein warping or distortion of the top bar of the upper door section may be prevented without resorting to interlocking means upon the elevator shaft adjacent the lintel of the door opening and carried by the door section, while still permitting the use of balancing or other weights and reinforcements secured 85 to this top bar structure.

To secure the desired results, I embody in the top bar structure a metallic angle bar, one of the flanges of which is permanently secured to the horizontal flange of the top bar proper of the door section, and the other flange or flanges of which project from this horizontal flange, the dimensions of this reinforcing angle bar being substantially the same as those of the angle metal of the top bar proper. In this manner, I not only secure the desired rigidity in the top bar structure as a whole to resist distortion of the top bar during the contraction of the metal thereof, but do so by means of a reinforcing part 100 of the bar having a rate of expansion and contraction substantially the same as that of the expansion and contraction of said top 105 bar.

bar proper, thus avoiding any resistance to the free expansion and contraction of the metal of the top bar.

The construction of the top bar throughout, is such as to afford large surface areas in both the frame angle bar proper and the reinforcing angle bar, for the radiation of heat, so that water directed against the top bar when it is at a high temperature will have a more or less uniform cooling effect upon both the bar proper and the reinforcing angle.

My invention is designed for use with doors having a corrugated, or a sheet metal panel, since it is not necessary with metal sheathed, wooden panel doors, in which construction the bars of the angle metal frame are so protected as to prevent the sudden cooling of the top bar thereof by the direction of a stream of water against same.

The invention consists primarily in a fire-proof elevator door, embodying therein a door section having a metal panel in an angle metal frame, and means for preventing the top of the door from moving away from adjacent the lintel of a door opening in the event of a sudden lowering of the temperature of the door following its subjection to a high temperature, including therein an angle metal reinforcing bar, one flange of which is connected with the horizontal flange of the angle metal of the top bar of the frame to form a unitary top bar structure, and another flange of which extends at right angles to the said flange of the angle of the top bar of the frame; and in such other novel features of construction and combination of parts as are hereinafter set forth and described, and more particularly pointed out in the claims hereto appended.

Referring to the drawings,

Fig. 1 is a plan view of a portion of a door section embodying the invention;

Fig. 2 is a vertical section through the top bar structure of the embodiment of the invention shown in Fig. 1;

Fig. 3 is a view similar to Fig. 2 showing another form of the invention; and

Fig. 4 is a view similar to Fig. 2 showing still another form of the invention.

Like letters refer to like parts throughout the several views.

In the embodiment of the invention shown in the drawings, the angle metal forming the top bar proper of the door section α is of the usual construction, dimensions and weight, the latter two of which may vary with doors of different sizes. A metal plate panel b is riveted, bolted or otherwise secured to the vertical flange a' of the angle α , the thickness of such plate and its relation to the door being such as to expose the entire under face of the horizontal flange a^2 of the angle α so that in the event of the subjection of the door to extremely high

temperatures, followed by a rapid lowering of the temperatures as by the direction of a stream against the door from the right, Figs. 2, 3 and 4, heat will be rapidly conducted from both flanges a' and a^2 , causing a rapid cooling throughout the angle α , accompanied by a considerable contraction or shrinkage of the material of this angle. The construction of the door section in other respects is such as to compensate for the expansion of the angle α when it is subjected to the higher temperatures, so as to avoid deformation of the door from such expansion.

As heretofore stated, the construction of the top bars of such doors has been such that the flange a' with the sudden lowering of its temperature, would contract rapidly, while the portion of the flange a^2 towards its free edge would contract much more slowly by reason of the restraint thereon from a counterbalancing weight in the form of a bar secured thereto and extending from side to side of the door, which bar contained a bulk of metal sufficiently great to cause a slow cooling of this bar as compared with the cooling of the flange a' . These conditions can arise only when the temperature of the metal of the angle α and the weight bar is about 1500 or 1600° F., thus causing these parts to be malleable to an extent to cause the buckling of the flange a' to force the flange a^2 and also the weight bar structure away from the wall of the shaft, the maximum amount of such movement being approximately at the vertical center line of the door opening.

To prevent this condition, I incorporate in the bar structure a reinforcing angle bar c , one flange c' of which extends substantially at right angles to the plane of the flange a^2 and the other flange c^2 of which is secured to the flange a^2 of the angle α , preferably in intimate contact therewith so as to permit the rapid conduction of heat from both flanges a^2 and c^2 in the event of a sudden lowering of the temperature after these flanges have been highly heated. The angle bar c thus forms a part of a unitary top bar structure of the door section. The flange c' extends beyond the frame of the door in a manner to provide a lapping of the door section beyond the door opening as required by various regulations and ordinances, and permits a reduction in the weight of material entering into the parts of the door section other than the angle c , while increasing the weight of the section as a whole.

If the character of the door requires the addition of weights to the door section carrying the angle c , I firmly secure a plurality of spaced, short, heavy bars d to the top bar structure of the door, the spacing of such bars avoiding continuity of the mass of such bars and permitting movement of the sev-

eral parts thereof with the expansion and contraction of the door without placing any restraint upon the flanges a^2 and c^2 . This arrangement is shown clearly in Fig. 1.

5 In the embodiment of the invention shown in Fig. 3, the angle metal frame is indicated at e , the opposite flanges thereof at e' and e^2 respectively, and the panel is shown at f .

Instead of using an L-angle bar as heretofore described, in this form of the invention I use a Z-angle bar g , one flange g' of which has the same relation to the flange e' of the frame angle as the flange c' has to the flange a' in the form of the invention shown in Figs. 1 and 2. The flange g^2 of the angle g is connected with the flange e^2 , so that the angle bar g is so united with the frame angle e as to form a part of a unitary top bar structure of the door section. The flange g^2 is spaced away from, and projects across, the edge of the flange e^2 and extends parallel with the flange e' .

In the embodiment of the invention shown in Fig. 4, the frame angle is shown at h , the vertical flange thereof at h' and the horizontal flange thereof at h^2 . With this construction, I use an L-angle i as a reinforcing member, one flange i' of which extends parallel with the flange h' and the other flange i^2 of which is connected with the horizontal flange h^2 . In this form of the invention the panel plate is indicated at j .

In the forms of the invention shown in Figs. 3 and 4, no weights corresponding with the weight d are shown, although such weights may be used if necessary.

Referring more particularly to Figs. 1 and 2 of the drawings, if the parts be brought to a temperature approximating a white heat, or even a lower temperature, the angles a and c , being of substantially the same dimensions and being engageable one with the other, will expand in unison, the slower heating of the weight bars d having no effect in preventing such expansion. By making these weight bars in sections and separating one from the other, the amount of expansion in each bar is reduced and the effect of the expansion so localized as to avoid any distortion of the top bar structure during expansion.

Assuming that a stream of cold water is directed against the top bar structure, particularly from the right, or the shaft side, the effect will be the sudden simultaneous cooling of both angles a and c , and consequently the simultaneous contraction of both these angles to substantially the same extent and throughout both flanges of each. The result is that there is no such buckling of the top bar structure as will materially increase the fire hazard as compared with a perfect door. While the flanges a' and c' may have the tendency to contract more rap-

idly than the joined flanges a^2 and c^2 , the difference in the rate of contraction is not so great but what the strength of the flanges a^2 and c^2 will offer sufficiently great resistance to the buckling tendency of the flanges a' and c' . In fact, the increased mass of 70 the material of the top bar structure between the flanges a' and c' will tend to retard contraction and shrinkage along this line and thus assist the flanges a^2 and c^2 in resisting deformation of the top bar structure 75 and give a tendency of the bar to buckle toward the shaft rather than away from it.

The weight bars d may be in such number and of such length as to be no appreciable factor in retarding either expansion or contraction of any portion of the top bar structure.

The form of the invention shown in Figs. 1 and 2 is suitable for medium width doors.

The form of the invention shown in Fig. 3 is especially adapted for use with wider doors than those shown in the forms of the invention shown in Figs. 1, 2 and 4. In this form of the invention, that shown in Fig. 3, the flange g^2 is so positioned as to be cooled 90 more readily than either of the flanges e' and g' , and will thus develop stresses counter to those developed in the flanges e' and g' and thus be effective in resisting the distortion of the latter flanges.

The form of the invention shown in Fig. 2 is preferable in most cases to that shown in Fig. 3, because less difficulties are encountered in manufacturing it and standard angle metals may be used in its construction.

In the form of the invention shown in Fig. 4, the condition is as shown in Fig. 3, except for the absence of the flange g' . The effect of this construction will be substantially that of Fig. 3, only there is no such increased bulk of material at the meeting point of the flanges h' and h^2 as is afforded by the use of the flange g' . In other respects the resistance to the distortion of the top bar 105 of the door construction shown in Fig. 4 110 is much the same as that shown in the construction of Fig. 3.

In all of the constructions shown, in the event of the high heating and sudden cooling of the door, the top bar structure will remain in close proximity to the wall of the elevator shaft without the assistance of binders of any kind, thus avoiding the necessity for special construction of door panels 115 and of lintels necessary with the use of such binders.

It is not my intention to limit the invention to the precise details of construction and dimensions of parts shown in the drawings, it being apparent that such may be varied without departing from the spirit 125 and scope of the invention.

Having described the invention, what I

claim as new and desire to have protected by Letters Patent, is:—

1. A fireproof elevator door, embodying therein a door section having a metal panel in an angle metal frame, and means for preventing the top of the door from moving away from adjacent the lintel of a door opening in the event of a sudden lowering of the temperature of the door following its 10 subjection to a high temperature, including therein an angle metal reinforcing bar, one flange of which is connected with the horizontal flange of the angle metal of the top bar of the frame to form a unitary top bar structure, and another flange of which extends at right angles to the said flange of the 15 angle of the top bar of the frame.

2. A fireproof elevator door, embodying therein a door section having a metal panel in an angle metal frame, and means for preventing the top of the door from moving away from adjacent the lintel of a door opening in the event of a sudden lowering of the temperature of the door following its 20 subjection to a high temperature, including therein an angle metal reinforcing bar, one flange of which is connected with the horizontal flange of the angle metal of the top bar of the frame to form a unitary top bar structure, and another flange of which extends at right angles to the said flange of the 25 angle of the top bar of the frame.

3. A fireproof elevator door, embodying therein a door section having a metal panel in an angle metal frame, means for preventing the top of the door from moving away 30 from adjacent the lintel of a door opening in the event of a sudden lowering of the temperature of the door following its subjec- 35

tion to a high temperature, including therein 45 an angle metal reinforcing bar, one flange of which is connected with the horizontal flange of the angle metal of the top bar of the frame to form a unitary top bar structure, and another flange of which extends at right angles to the said flange of the top bar of the frame, and a plurality of weights supported from said reinforcing bar and spaced apart in relation to each other, whereby the presence of these weights 50 will have no material distorting effect upon the top bar during the expansion or contraction of said top bar structure of the door.

4. A fireproof elevator door, embodying 60 therein a door section having a metal panel in an angle metal frame, means for preventing the top of the door from moving away from adjacent the lintel of a door opening in the event of a sudden lowering of the 65 temperature of the door following its subjection to a high temperature, including therein an angle metal reinforcing bar, one flange of which is connected with the horizontal flange of the angle metal of the top 70 bar of the frame to form a unitary top bar structure, and another flange of which extends at right angles to the said flange of the angle of the top bar of the frame in substantial alinement with the vertical 75 flange of the top bar of the frame, whereby said projecting flange will be included in that part of the door which laps the lintel of the door opening, and a plurality of weights supported from said reinforcing 80 bar and spaced apart in relation to each other, whereby the presence of these weights will have no material distorting effect upon the top bar during the expansion or contraction of said top bar structure of the door. 85

In witness whereof I have hereunto affixed my signature this 28th day of June, 1926.

PAUL R. SAURER.
